UNITED STATES PATENT OFFICE

ARTHUR B. LOW, OF DENVER, COLORADO

DESIGN FOR A BEVERAGE OR FOOD TABLET

Application filed July 21, 1932. Serial No. 44,391. Term of patent 14 years.

To all whom it may concern:

Be it known that I, ARTHUR B. Low, a citizen of the United States, residing in the city and county of Denver, State of Colorado, have invented a new, original, and ornamental Design for Beverage or Food Tablet, of which the following is a specification, reference being had to the accompanying drawing, forming part thereof.

Figure 1 is a plan view of a beverage or food tablet constructed in accordance with the present invention.

Figure 2 is an edge view of the same.

I claim:

The ornamental design for beverage or food tablet, as shown.

ARTHUR B. LOW.
